UNITED STATES PATENT OFFICE.

MARCUS O. ANTHONY, OF ENGLEWOOD, NEW JERSEY, ASSIGNOR TO A. KIMBALL COMPANY, OF NEW YORK, N. Y., A CORPORATION OF NEW YORK.

CARD-FEEDING MECHANISM FOR PRINTING-MACHINES.

1,186,644.

Specification of Letters Patent. Patented June 13, 1916.

Original application filed June 27, 1914. Serial No. 847,698. Divided and this application filed December 15, 1914. Serial No. 877,435.

To all whom it may concern:

Be it known that I, MARCUS O. ANTHONY, a citizen of the United States, and resident of Englewood, county of Bergen, State of New Jersey, have invented an Improvement in Card-Feeding Mechanism for Printing-Machines, of which the following description, in connection with the accompanying drawing, is a specification, like characters on the drawing representing like parts.

This invention relates to improvements in card feeding mechanism for printing machines and the like and as illustrated herein is shown as adapted to a pin ticket printing machine of the character shown in my co-pending application No. 847,698 filed June 27th, 1914 of which this application is a division.

The principal object of the invention is to provide a magazine for supporting a plurality of cards or pin tickets and means for delivering the same one by one with certainty to the printing mechanism or other operative mechanism.

A further object of the invention is to provide means for temporarily arresting the cards or pin tickets as they are dropped from the magazine before they reach printing position and thereafter releasing the same so that they will drop into operative position without rebounding, thereby insuring the accurate positioning of the ticket.

Other features of the invention and the nature thereof will more fully appear from the following description and the accompanying drawings and will be particularly pointed out in the annexed claims.

In the drawings: Figure 1 is a side elevation of a printing machine provided with feeding mechanism embodying my invention, Fig. 2 is a front elevation of the same, Fig. 3 is a vertical longitudinal sectional view through the magazine, the printing mechanism including the chase and oscillating platen, Fig. 4 is a sectional view on lines 4-4, Fig. 3, of the ticket magazine, the tickets having been omitted, looking downward, showing the guiding means for directing the ticket or card into printing position, Fig. 5 is a detail plan view of the platen and means for vertically adjusting the same, and, Fig. 6 is an illustration of a pin ticket.

The printing machine to which the present feeding mechanism is applied comprises a main frame consisting of a base 1 and 55 preferably integral standards 2, 3, having ways 4 and 5 in which are slidably mounted the ends 6, 7 of a carriage 8 in which a chase 9 carrying type is slidably mounted, preferably upon cylindrical rods 10 and 11 secured to ends 6, 7 of the carriage 8. The sliding movement of the carriage is for the purpose of permitting it to be positioned in proper relation to the bed of the printing mechanism and also to be placed in proximity to the end of a type magazine having a plurality of chambers from which the type may be introduced directly into the chase or distributed therefrom into the proper chambers of the magazine. The printing mechanism includes a bed 12 which desirably may be the surfaced base of an integral standard 13 extending upwardly from the base 1 and desirably provided with a strengthening rib or web 14. The chase is 65 adapted to be positioned immediately in front of the bed 12 so that the bed forms a backing for the type carried by the chase. The card or pin ticket is pressed against the face of the type or against an inked ribbon interposed between the face of the type and the card, by an oscillating platen 15 suitably supported upon an arm 16 which is secured to a pivotal shaft 16^a mounted in journals in an adjustable base plate 17 resting upon the bed 1. The platen may be oscillated in any desired manner. As disclosed herein, the operating mechanism comprises a pitman 18 pivotally connected to the arm 16 and having its strap embracing an 70 eccentric 19 upon a shaft 20 mounted in suitable supports 21 extending upwardly from a standard 22 secured to the bed of the machine. The shaft 20 is provided with a gear 24 which meshes with a worm 25 upon 75 the shaft 26 of a suitable electric motor 27 which may be supported in any convenient manner from the base of the machine as by means of ears 28 extending from the motor casing and secured to a standard 29 extending upwardly from the bed plate by means of a bolt.

The type magazine is preferably rotatably mounted in bearings at the upper ends

of suitable standards and may be located in any convenient position relative to the printing mechanism, the delivery end of the magazine being so disposed that the chase 5 may be shifted from printing position in proximity to the end of the type magazine to permit the type to be introduced directly into the chase. The type magazine and the mechanism for operating the same are fully disclosed and claimed in my co-pending application and further description thereof in the present application is therefore unnecessary. It is sufficient to say that the type may be introduced from the magazine directly into the chase and when the proper subject matter is set up the chase may be transferred along the guide rods 10-11 until it is positioned immediately in front of the bed 12 as above described, whereupon 15 the printing mechanism is set in motion and the cards or pin tickets printed in the usual manner. In supplying cards to the printing mechanism I have found it desirable to provide a gravity feeding magazine comprising a chute supported upon the printing mechanism and provided with selecting mechanism adapted to release and deliver the lowermost card or pin ticket in the chute to the printing mechanism and at the same 20 time positively restrain the remaining cards or pin tickets in the chute from delivery to the printing mechanism.

As illustrated herein the chute comprises a stand 30 suitably secured upon the upper 25 end of the standard 13 by screws 31 or other suitable fastenings. This standard is desirably provided with grooved ways 32 adapted to receive a removable guide plate 33 which is adapted to direct the article to 30 be printed to the printing mechanism. The guide plate 33 is desirably formed with a pair of parallel ways 34 the edges of which are spaced apart a sufficient distance to receive the card or pin ticket to be printed 35 and are united by a web 35 which is adapted to extend from the base of the stand 30 to the chute and is beveled off at its upper end to form a continuation of the bottom of the chute, as illustrated in Fig. 3. The forward wall of the ways may be formed by plates 36 suitably secured to the guides 33. Pins 37 inserted in the guide 33 near its upper end and adapted to rest upon the upper end of the stand 30 form a convenient 40 means for supporting the removable guide in position. It will be understood that guides of various widths may be provided which will be adapted to direct pin tickets or cards of different sizes to the printing 45 mechanism and that one guide can be substituted for another by merely withdrawing the guide vertically from the guideway and inserting another. The magazine or chute above described should correspond in 50 size to the largest pin tickets which are to

be printed and several chutes of smaller size may be provided which may be telescoped within the main chute, the widths of the smaller chutes corresponding to the widths of the respective guideways.

The cards or pin tickets are arranged in the chute in overlapping position as illustrated in Fig. 3 and are desirably supported at the lower end of the chute by a ledge 40 having a recess 41 communicating with 55 an aperture 42 through the base of the chute, a trip 43 for delivering the pin tickets one at a time being adapted to be reciprocated and oscillated within these apertures in a manner which will hereinafter be described. When 60 pin tickets are used the pins of each ticket rest upon the upper edge of the next lowermost card and support the tickets in the manner illustrated in Fig. 3. If, however, plain tickets are to be printed a stepped 65 block may be provided to maintain the tickets in substantially the same overlapped position, as illustrated in Fig. 3.

The trip 43 desirably is pivotally mounted upon the plate 44 which in turn is mounted upon the shaft 45 journaled in suitable bearings 46 on the underside of the chute, the shaft 46 being provided with an arm 47 which is oscillated through a link 48 connected to an arm 49 which is rigidly secured to and oscillates with the pivotal shaft 16^a of the platen supporting arm 16, (see Fig. 1). The arm 49 is preferably attached to the pivotal shaft by means of a set screw 50 so that the arm may be rotatably adjusted upon said shaft to provide for the proper timing of the releasing and feeding mechanism relatively to the reciprocation of the platen. It will be obvious that upon each oscillation of the platen the arm 49 100 will be oscillated causing a reciprocation of the link 48 which in turn will oscillate the arm 47 and its attached shaft 46 causing an oscillation of the plate 44 which will withdraw the trip 43 to the aperture 42 in the 105 bottom of the chute.

In order to release the lowermost card or pin ticket in the chute and to retain the remaining cards or pin tickets the trip 43 is 110 preferably provided at its end with a thin lip 51, the trip being so directed in its movement that upon withdrawal it will be depressed into the recess 41 of the ledge and will pass beneath the lower end of the pile of cards or pin tickets. Upon its forward movement the lip 51 will engage the under surface of the lowermost pin ticket and raise the same out of engagement with the ledge 40 permitting the ticket to drop into the guide whence it is delivered to the printing mechanism.

The means for giving the trip 43 a desired movement in the construction disclosed herein comprises a cam 52 supported upon an arm 53 which is pivotally mounted upon a 130

stud 54 projecting laterally from a bracket 55 secured to the under portion of the chute. Limiting stops 56 and 57 may be provided to determine the amplitude of oscillation of the arm 53 which carries the cam 52 aforesaid.

The trip 43 is provided with a laterally extending stud 58 which upon the outward movement of the oscillating plate 44 engages the flat upper surface of the cam 52 riding upwardly over the same thus depressing the top end of the trip so that the lip 51 will pass beneath the lowermost pivot which is supported upon the ledge 40. Upon further outward movement of the plate 44 the stud 58 rides over the end of the cam 52 and drops beneath the same so that upon forward movement of the oscillating plate 44 the lip 51 and the trip will rise beneath the end of the lowermost card or pin ticket and the continuous forward movement will thrust the body of the card from the ledge 40 whence it will drop into the chute in the manner aforesaid.

It will be understood that the mechanism for delivering the pin tickets from the chute is operated directly from the movement of the platen and the mechanism is desirably so timed that the cards or pin tickets drop as the platen is approaching printing position. The chute is necessarily supported some distance above the printing mechanism and it is found that if the cards or pin tickets are permitted to drop directly into printing position before being arrested they will be likely to rebound in such a manner that they will be improperly positioned in respect to the printing mechanism when engaged by the platen. In order to avoid this contingency I have provided mechanism for arresting the tickets in their descent just before they reach printing position and for releasing the same as the platen approaches final position so that they will be held in proper position when engaged by the platen.

The present invention is shown as adapted to the printing of pin tickets and to accomplish the purpose thus described means are provided for engaging the pins of the dropping pin ticket and for supporting them slightly above the final position, this supporting means being removed as the platen comes forward so that the pin tickets may be dropped until they are supported by their pins upon the platen as it reaches its printing position. In the preferred embodiment of the invention disclosed herein this arresting mechanism comprises an L-shaped plate 60, the forward projection 61 of which is adapted to engage the pins *b* of the pin tickets *a* as the latter drop through the guide 33. This L-shaped plate preferably is supported upon a shaft 62 mounted in bearings 63 in lugs extending from the stand 30, the shaft 62 being provided with an arm 64 which engages the projecting end of the rod

65 carried at the lower end of the plate 44. By this arrangement the plate 60 is moved into the vertical position shown in Fig. 3 just at the time the pin ticket is released from the chute by the trip 43, the platen at 70 that time being in substantially fully retracted position. As the platen moves forward toward the chase the plate 44 moves gradually away from the chute causing the L-shaped member 60 to be oscillated back- 75 wardly withdrawing the forward projection 61 from beneath the pins *b* of the pin ticket *a*, so that slightly before the platen reaches printing position the pins *b* of the pin ticket *a* will be released and the ticket will drop 80 until arrested by the pins engaging the upper end of the platen 15.

The platen 15 is desirably provided with means for adjusting the same vertically so that lines *c* upon the pin ticket *a* may be positioned properly in respect to the lines of type in the chase. 85

In order to provide for a suitable adjustment the platen is provided with a tenon 66 slidably mounted in a dove-tailed groove 67 90 in the upper end of the arm 16. The platen is provided with a laterally extending arm 68 which is provided at its end with a setscrew 69 resting upon the upper end of the arm 16 by means of which the platen may 95 be adjusted vertically in respect to the end of the arm.

In operation the magazine is filled with cards or pin tickets so arranged that the same overlap as illustrated in Fig. 3. The printing mechanism is then set in operation and the platen oscillates toward and from the type in the usual manner. By reason of the fact that the shaft upon which the platen is pivoted is secured by links to the plate 44 each oscillation of the platen will cause an oscillation of the plate 44 and the mechanism which is attached thereto. The oscillation of the plate 44 as above described causes the reciprocation of the trip 43 which 110 is guided in its movement by the cam 52 so that the lip 51 from the backward movement descends into the aperture 41 of the ledge 40 and the aperture 42 in the bottom of the chute 38 so that the lip passes beneath the lowermost card, as the pin 58 on the lip 43 rides over the end of the cam 52 the lip 51 rises beyond the lowermost card or pin ticket and engages the rear surface thereof. The forward or upward movement 115 of the plate 44 thereupon causes the lip 51 to separate the lower end of the lowermost ticket from the one immediately beneath it and upon further forward movement serves to thrust this ticket over the edge of the ledge so that it will drop into the guideway and be conducted to the printing mechanism, the lip 51 in the meantime has passed beyond the end of the next lowest pin ticket 120 or card and arrested the same in the posi- 125 130

tion shown in Fig. 3. As the released ticket descends its pins *b* strike the horizontal portion *61* of the L-shaped arresting device *60* holding the pin tickets slightly above printing position. As the platen comes forward the L-shaped support *60* rocks about its pivot *62* by reason of the fact that the arm *64* which rests upon the rod *65* carried by the plate *44* is caused at this time to descend by the action of the feeding mechanism which is connected with the shaft of the platen so that as the platen approaches printing position the arresting member *60* is entirely removed from its engagement with the pins of the pin ticket and the pins thereupon drop upon the upper end of the platen. As heretofore described the platen is adjustable upon its supporting iron so that the lines *c* upon the pin ticket may be accurately positioned in respect to the lines of type upon the chase.

When the ticket or card has been printed and the platen withdrawn the edges of the pin ticket are retained by the plates *36* of the guide so that when the top of the platen is withdrawn from beneath the pins the tickets will slide downwardly to the bottom of the guideway from which there may be a suitable discharge chute at any convenient place, as for example, in front of the machine.

It will be understood that although this mechanism is described particularly in relation to machines for printing pin tickets that the same may be adapted to other uses in printing machines and in other machines in analogous arts. It will also be obvious that the arresting mechanism may be so disposed as to engage the bottom of the ticket to position the same properly in alignment with the top upon the chase instead of engaging the pins as above described. It is also to be understood that various and sundry changes may be made within the contemplation of my invention set forth in the following claims.

Having thus described my invention what I claim as new and desire to secure by Letters Patent is:

50 1. Feeding mechanisms for printing machines comprising a magazine or chute supported above the printing machine and having a retaining member adjacent its lower end adapted to support a series of overlapped articles by engagement with the lowermost articles only and means operated in timed relation to the printing machine for successively releasing the lowermost article from said retaining member whereby the same may be dropped to printing position.

2. Feeding mechanism for printing machines comprising a magazine or chute having a retaining member adjacent its lower end adapted to support a series of over-

lapped articles, means operated in timed relation to the printing machine for successively releasing the lowermost article from said retaining member including a trip and means for retracting the same beneath the lowermost article and for thereafter raising the end of said trip to engage the said article and to thrust the same from engagement with the releasing member.

3. Feeding mechanism for printing machines comprising an inclined chute having a recessed ledge adjacent its lower end adapted to support a series of articles, a member pivotally supported by said chute and oscillated in proper timing with the printing machine, a trip pivotally mounted upon said member adapted to be reciprocated through an aperture in said chute, means adapted to engage said trip to depress the same during its retracting movement and to elevate the same during its forward movement whereby the lip of said trip will be caused to engage the lowermost article and thrust the same from engagement with said ledge and thereby deliver said article to the printing machine.

4. Feeding mechanism for printing machines comprising an inclined chute having a recessed ledge adjacent its lower end adapted to support a series of articles, a member pivotally supported by said chute and oscillated in proper timing with the printing machine, a trip having a thin upwardly projecting lip pivotally mounted upon said member adapted to be reciprocated through an aperture in said chute and the recess in said ledge, a pivotally mounted cam supported upon the chute adapted to engage said trip to depress the same during its retracting movement to cause the lip to pass beneath the lowermost article and to elevate the same during its forward movement whereby the lip of said trip will be caused to engage the lowermost article and thrust the same from engagement with said ledge and thereby deliver said article to the printing machine while retaining the next lowermost article upon said ledge.

5. Card feeding mechanism for printing machines comprising an inclined magazine or chute for the cards, superposed upon the printing machine, a guideway leading from said chute to said printing machine and a telescopically removable guide mounted in said guideway between the delivery end of the chute and the printing machine, whereby guides of different widths may be provided for cards of different sizes.

6. Card feeding mechanism for printing machines comprising a chute having a plurality of telescoping parts superposed upon the printing machine, a guideway leading from said chute to said printing machine and a telescopically removable guide mounted in said guideway between the delivery

end of the chute and the printing machine whereby chutes and guides of different widths may be provided for pin tickets of different sizes.

5 7. Card feeding mechanism for printing machines comprising a chute adapted to support the pin tickets to be printed, means actuated in timed relation with the printing machine to release said pin tickets one at a time from said chute to permit them to drop to the printing machine, means to arrest the pin tickets before reaching printing position and means for withdrawing said arresting means to permit said ticket to drop to

15 printing position.

8. Card feeding mechanism for platen printing machines comprising a chute adapted to support the pin tickets to be printed, means actuated in timed relation 20 with the printing machine to release said pin tickets one at a time from said chute to permit them to drop to the printing machine, means adapted to engage the pins of the dropping ticket to arrest the same before reaching printing position, and means 25 to withdraw said arresting means from engagement with said pins upon the forward movement of the platen to permit the pins to engage the platen and the pin ticket to be 30 supported thereby during the printing operation.

9. Card feeding mechanism for platen printing machines comprising a chute adapted to support the pin tickets to be 35 printed, means actuated in timed relation with the printing machine to release said pin tickets one at a time from said chute to permit them to drop to the printing machine, a pivotally mounted member adapted 40 to engage the pins of the dropping ticket to arrest the same before reaching printing position, and means operated by the ticket releasing mechanism to withdraw said arresting member from engagement with said 45 pins upon the forward movement of the

platen to permit the pins to engage the platen and the pin ticket to be supported thereby during the printing operation.

10. Card feeding mechanism for platen printing machines comprising a chute 50 adapted to support the pin tickets to be printed, means actuated in timed relation with the printing machine to release said pin tickets one at a time from said chute to permit them to drop to the printing machine, means adapted to engage the pins of the dropping ticket to arrest the same before reaching printing position, and means to withdraw said arresting means from engagement with said pins upon the forward 55 movement of the platen to permit the pins to engage the platen and the pin ticket to be supported thereby during the printing operation, and means for adjusting the platen whereby the lines upon the pin ticket 60 may be positioned properly in relation to the lines of type in the chase.

11. Card feeding mechanism for platen printing machines comprising a magazine adapted to support the pin tickets to 70 be printed, means to release the pin tickets one at a time from said magazine, a guide for the dropping tickets, means adapted to engage the pins of the dropping ticket before reaching printing position, means for 75 withdrawing the engaging means upon the forward movement of the platen to permit the pins to engage the platen and the pin ticket to be supported thereby during the printing operation, said guide acting to hold 80 the printed ticket as the platen is withdrawn, thereby to deliver the printed ticket.

In testimony whereof, I have signed my name to this specification, in the presence of two subscribing witnesses.

MARCUS O. ANTHONY.
